UNITED STATES PATENT OFFICE.

LYCURGUS W. MORTER, OF SEDALIA, OHIO, ASSIGNOR OF ONE-THIRD TO XERXES FARRAR AND ONE-THIRD TO HARRY S. MITCHELL, BOTH OF LONDON, OHIO.

PORTABLE LOADER.

1,222,973.

Specification of Letters Patent. Patented Apr. 17, 1917.

Application filed August 14, 1916. Serial No. 114,731.

To all whom it may concern:

Be it known that I, LYCURGUS W. MORTER, a citizen of the United States, residing at Sedalia, in the county of Madison and State of Ohio, have invented certain new and useful Improvements in Portable Loaders, of which the following is a specification.

My invention relates to portable loaders which may be put to any one of a number of uses. My loader is particularly adaptable 10 in picking fruit or vegetables or corn, in which case it may be placed upon the ground and the articles tossed or placed upon it until a sufficient quantity has been gathered. Then, the handles may be grasped and the 15 entire structure transported.

The main object of this invention resides in so shaping the longitudinal supports that a receiving base is formed, which is concaved in all directions, thus causing whatever 20 article may be placed upon it, to tend to roll toward the center of the loader as a whole.

The preferred embodiment of my invention is shown in the accompanying sheet of 25 drawings, in which similar characters of reference designate corresponding parts, and in which:

Figure 1 is a view in perspective showing 30 my loader in a position suspended above the ground,

Fig. 2 is a transverse section of the same, and,

Fig. 3 is a view in side elevation of the same.

In these several views, there is shown a 35 pair of side supports designated 1, which may be formed of pipe or bars as may be desired. The essential feature in forming these supports is that the portions intermediate the ends, should be slightly concaved such as is shown at 2. In the present case, I have formed handles 3 on the ends of each 40

of the bars, by giving them a sharp bend, as is shown. To these side supports there is then attached a flexible supporting member 45 4, which member may be sewed or removably secured along the edges shown at 5, as may be desired.

By forming the side supports concaved at 2, the natural tendency of these bars is to 50 pivot slightly about the handle portions 3 when these handles are grasped for transportation, so that the concaved portions will be swung inwardly to a slight extent, as is indicated in Fig. 2, which in turn causes the 55 supporting member 4 to assume a shape which is concaved in all directions. This prevents whatever goods may be placed on the same from rolling or falling off of the 60 same.

Thus, it will be apparent that I have provided a very simple type of loader, but which is nevertheless very effective in supporting the goods.

What I claim, is:

1. A portable loader of the character described comprising a pair of side supports carrying handles on each end and concaved intermediate said handle portions, and a flexible receiving member attached to said 70 supports at the concaved portions.

2. A portable loader of the character described comprising a pair of side supports each formed of a single bar or rod shaped to present handles on each end and a concaved portion between handles, and a flexible receiving member attached along opposite edges to said supports between their handles.

In testimony whereof I affix my signature in presence of two witnesses.

LYCURGUS W. MORTER.
